UNITED STATES PATENT OFFICE.

GEORGE BOXLEY, OF TROY, NEW YORK, ASSIGNOR OF ONE-HALF TO
GEORGE P. IDE BRUCE & CO., OF SAME PLACE.

COMBINED BUTTON-LAP AND STAYING-PIECE FOR GARMENTS.

SPECIFICATION forming part of Letters Patent No. 297,746, dated April 29, 1884.

Application filed January 21, 1884. (No model.)

To all whom it may concern:

Be it known that I, GEORGE BOXLEY, of the city of Troy, county of Rensselaer, State of New York, have invented a new and useful 5 Improvement in Combined Button-Laps and Staying-Pieces for Garment Slit-Openings, of which the following is a specification.

My invention relates to that class of attachments which are applied to the slit-openings 10 of garments, and more particularly to the back-openings and side sleeve-openings of shirts, the object and purpose of which attachments are to produce a fly-lap for button-connection, and to secure the terminal end of the 15 slit so as to prevent it from being ruptured at that point.

Accompanying this specification and forming 20 a part of it there are two sheets of drawings, containing four figures illustrating my invention, with the same designation of parts used in all of them.

Of these illustrations, Figure 1 shows the 25 form of the strip used to produce my invention by its form and attachment. Fig. 2 illustrates the position of the strip after having been attached to each side of the garment-slit with its other edges free. Fig. 3 shows the 30 strip as attached to form a button fly lap and stay for a shirt-back opening. Fig. 4 shows a section taken through the attached parts on the line α/α' of Fig. 3, with the thickness of the parts exaggerated, to better illustrate them.

The strip and the folds produced in it, the 35 shirt-back and its parts, with which the strip connects, are designated by letter-reference, and the several process steps by which the said strip or placket is attached to the part of shirt-back shown are detailed and described as follows:

40 The letter A indicates the strip or placket, and C a portion of a shirt-back made with the opening O, the latter being a slit, of which c/c' are the side edges. This strip or placket is made to gradually taper from one end to the 45 other, and is made of sufficient length to form in continuity the outer facing of the under lap, the outer and inner facing of the button fly lap, and the staying tab-end below the slit.

To attach the strip or placket, the two re-

versing cross-folds m/m' are made in it, so as 50 to produce the three facing-folds $F/F'/F''$, and the staying tab-end T. As it is thus folded, the strip is placed as shown in Fig. 1, in which position the edges of the facing-folds F/F' upon one of the adjacent edges of each are sewed, as 55 indicated at S' , and then turned on the line of such union to produce the outer and inner fac- 60 ing of the fly when applied with the parts, ap- 65 pearing as indicated at Fig. 2. When this has been done, the free edges of the strip-folds F/F' are turned in coincidently with the edges 70 of the slit and sewed thereto, as shown at S/S' . Following this the remaining free edge of the strip-fold F'' is turned in and sewed to the shirt-back, as indicated at S'' . The free 75 edge of the strip-fold F'' is also sewed exteriorly to the shirt-back at S'' , the edge of the strip being turned in, and the tab-end T is also stitched to the shirt-back exteriorly below the slit at S' , the edges of the tab-end being turned 80 in. To complete the attachment, the connected 85 folds of the strip are cross-sewed to the shirt and to each other at the bottom of the slit, as indicated at S''/S'' .

I am aware of the fact that a continuous strip 75 of a uniform width as combined with various methods of attachment has been patented, but which methods and form of strip required the accumulation of an unnecessary amount of ma- 80 terial at the top of the slit-opening, which, when laundered, made the parts stiff and difficult to button, and which aggregation of ma- 85 terial at this point produced much discomfort to the wearer during hot weather.

By the use of a tapering strip or placket I 85 am enabled to secure all the accumulation of material where it is needed to give strength to the parts, and to use less where its accumu- lation is objectionable.

While I have shown and described the use 90 of a strip made to taper uniformly in width, if desired, that part of it which, when folded, produces the outer facing of the underlap and that forming the inner facing of the button- 95 fly or overlap may be made to have less taper than that fold which produces the outer fac- ing of the latter and the tab-end stay at the bottom of the slit.

Having thus described my invention, what I claim, and desire to secure by Letters Patent, is—

1. In combination with the slit-opening of a garment, the tapering strip or placket A, made in one piece that is oppositely folded to produce the facings F' F² F³, with the adjacent edges of the facing-folds F' F² on one side united, as shown, and the remaining free edge 10 of the fold F² sewed to one side of the slit, and the free edge of said fold F' to the garment exterior, with the facing-fold F³ on its inner edge sewed to the adjacent edge of the slit, and its other edge to the garment exterior, and with 15 said connected parts cross-sewed to the garment and to each other below the slit, as described.
2. In a combined button lap and stay for garment slit-openings, the combination of the strip or placket A, made in one piece and reversely folded to produce the facing-folds F' F² F³ and tab-end stay T, the stitching S', uniting on one of their sides the edges of the folds F' F², the stitching S² S³, connecting said fold-

facings F' F² to the edge of the slit-opening 25 and the exterior of the garment, the stitching S² S³, uniting the said facing-fold F³ to one side of the slit and to the garment exterior, the cross-stitching S⁶, joining said connected folds to the garment and to each other below the 30 slit, and the stitching S⁷, uniting said tab end stay to the garment below the slit, as shown.

3. In a button fly lap and stay for garment slit-openings, the combination of the tapering strip or placket A, made in one piece, the reversing-folds m' m², made in the strip, the facing-folds F' F² F³, the stitching S', connecting on one side the adjacent edges of the facings F' and F², and said facings F' F² F³, adapted to attach to the garment-slit and garment exterior, as shown and described.

Signed at Troy, New York, this 7th day of January, 1884, and in our presence, whose names were by us hereto written.

GEORGE BOXLEY.
